Primary Examiner — Philip S Hyder(74) *Attorney, Agent, or Firm* — Steve LeBlanc, LLC(57) **CLAIM**

The ornamental design for a blade, as shown and described.

DESCRIPTION

FIG. 1 is a top, right perspective view of a blade, showing the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines depict portions of the blade in which the design is embodied that are not considered part of the claimed design.
